COMPRESSOR CONTROLLING MECHANISM

Filed Aug. 10, 1923

UNITED STATES PATENT OFFICE.

CHARLES B. OFFICER, OF CHICAGO, ILLINOIS, ASSIGNOR TO SULLIVAN MACHINERY COMPANY, A CORPORATION OF MASSACHUSETTS.

COMPRESSOR-CONTROLLING MECHANISM.

Application filed August 10, 1923. Serial No. 656,736.

My invention relates to compressor controlling mechanism, and more particularly to controlling mechanism for electrically driven compressors.

5 An object of my invention is to provide an improved compressor system. Another object of my invention is to provide an improved compressor system in which the compressor is driven by an electric motor and forms only a portion of the electrically 10 driven equipment of a shop or plant. In view of the relation that peak demand bears to current cost it is desirable to maintain the peak demand as little above the maximum running demand as is possible. It is therefore undesirable, when the compressor is 15 running unloaded, for it to take its load at a time when other motors forming the remaining portion of the equipment of the plant are being started up, for by maintaining the compressor momentarily unloaded until the other motor or motors have assumed their normal running characteristics, it will 20 be possible to reduce the peak demand for the current materially. It is a more specific 25 object of my invention to provide an improved controlling mechanism for a compressor which will prevent the loading of the compressor at such time as other motor driven equipment of a shop is drawing so 30 heavily on the supply lines that an excessive current demand would be created by the throwing of the load upon the compressor driving motor. Other objects and advantages 35 of my invention will hereinafter more fully appear.

In the accompanying drawings I have shown for purposes of illustration one form which my invention may assume in practice.

40 In these drawings,

Fig. 1 is a view partially in side elevation and partially diagrammatic showing a compressor system constructed in accordance with one illustrative embodiment of my invention.

Fig. 2 is a detail sectional view through a portion of the controlling mechanism.

In the illustrative embodiment of my invention I have shown the same employed in a shop or other plant in which there are for purposes of simplicity of disclosure, but two motors shown, these being designated respectively 1 and 2, although it will be understood that there may be a plurality of motors besides the compressor driving motor. Each

of these motors is provided with a controlling switch, herein only diagrammatically illustrated, but respectively designated 3 and 4. Motor 1 may be used for any purpose while motor 2 is the driving motor for a 60 compressor 5 which is herein shown as of the angle-compound type comprising a low pressure cylinder 6 discharging through an intercooler 7 which in its turn opens into the high pressure cylinder 8 arranged at right 65 angles to the low pressure cylinder 6. The high pressure cylinder 8 in its turn discharges through a pipe line 9 to a receiver 10. Suitable intake closure unloading mechanism generally designated 11 is arranged to cooperate with the low pressure cylinder 6 and for the purpose of controlling this mechanism a pipe line 12 leads from the receiver 10 and communicates with a pilot valve 13. When the receiver pressure is in excess of a 70 predetermined amount the pilot valve 13 will permit the passage of fluid from the pipe 12 to the unloading mechanism 11 and will cause closure of the intake unloading valve and so unloading of the compressor. 75 When on the other hand the receiver pressure falls to a certain fixed limit, the pilot valve 13 will close and will vent unloading mechanism 11 and cause reloading of the compressor to take place. The two motors 80 1 and 2 take their current from line conductors 15, 16 controlled by a main line switch 17.

As one possible example of a plant in which my invention will be desirable, let 90 it be assumed that the combined full load current demand of both motors is less than the current that will be taken with the compressor running unloaded and with the other motor starting, so that the last mentioned 95 condition may determine the peak demand. It would evidently be undesirable to reload the compressor at a moment when the motor 1 was starting, as this would carry up the current demand above the maximum stated. 100 Accordingly, means is provided for controlling the loading of the compressor controlled by the current taken from line conductors 15, 16 operative to prevent loading when the current drawn is equal to the demand when 105 motor 1 is starting and motor 2 running with the compressor unloaded. This is accomplished by arranging beyond the main line switch 17 in the line conductor 16, which leads to one side of the motors a rel- 110

atively heavy coil of a few turns in series in the line. A plunger 19 is arranged within this coil and depending upon the current taken by the motors the field of this magnet 5 will be increased or diminished. The switch 20 is arranged in a manner to be controlled by the plunger 19, herein being connected thereto by a link 21 which may preferably be constructed of insulating material so as 10 to prevent any undesired current flow or chance of injury. The spring 22 prevents the closure of the switch 20 except in case the current flowing through the coil 18 rises to the value determined upon. The switch 15 20 controls a circuit including lines 23 and 24 and also including the solenoid 25. A plunger 26 is arranged within the solenoid 25 and is connected to a piston valve 27 in a chamber 28 which is arranged in a by-pass 29 connecting the line 12 to the unloading mechanism 11 and shunting the pilot valve 13. It will be noted that the piston valve 27 is normally maintained in a position to interrupt communication between 25 the mechanism 11 and the line 12 but that when the solenoid 25 is energized the piston valve will be moved to open communication through the line 29. It will of course be understood that pressure admitted through 30 the line 29 and shunt into the unloading mechanism by closure of valve 27 will be vented by the pilot valve 13, but that the rate of supply through the passage 29 is greater than can be taken care of by the 35 vent in the pilot valve 13.

The mode of operation of this mechanism will be clearly apparent. Assume that the motor 2 is running, and that the compressor is loaded. When motor 1 is thrown upon 40 the line, the current passing through the coil 18 will be so great as to instantly cause closure of the switch 20 and the energization of the coil 25 will cause the plunger 26 to move the valve 27 to admit pressure to unload the compressor by its action in the unloading mechanism 11. This action will 45 obviously be very rapid and will reduce the current consumption so quickly as to avoid an increased rate. Consider again that the 50 compressor is unloaded and that it is intended to start the motor 1 and that just as the motor 1 is starting the pilot valve 13 should operate to vent the unloading mechanism. This would permit the compressor to 55 load but for the operation of the solenoid 18 which being again energized sufficiently to close the switch 20 would cause the passage of fluid through the by-pass 29 and prevent re-loading until after the current demand of 60 the motor 1 had dropped.

While I have in this application specifically described one form which my invention may assume in practice, it will be understood that this form of the same is shown for purposes of illustration and that the invention

may be modified and embodied in other forms without departing from its spirit or the scope of the appended claims.

What I claim as new and desire to secure by Letters Patent is:

1. In combination, a compressor, a plurality of motors including a motor for driving said compressor, a source of electric current for driving said motors, and unloading means for said compressor including a plurality of operating medium supplies one of which is controlled by the current drawn by the motors from said source and another of which is independent of said electric current, said current controlled supply being adapted to deliver operating medium for unloading the compressor if the independent supply should induce loading of the compressor when the current consumption from said source exceeds a predetermined amount. 75 80 85

2. In combination, a compressor, a receiver, a plurality of motors including a motor for driving said compressor, a source of electric current for driving said motors, and unloading means for said compressor including a plurality of operating medium supplies one of which is controlled by fluid pressure in said receiver and a second of which is controlled by the current drawn from said source by said motors. 90 95

3. In combination, a source of electric current, a plurality of motors adapted to be supplied from said source, a compressor driven by one of said motors, unloading means adapted to unload said compressor upon actuating medium being supplied to said means, compressor discharge pressure governed controlling means for the supply of such medium, and means for taking the control of the supply away from said last mentioned means governed by a predetermined amount of current drawn from said source by said plurality of motors. 100 105

4. In combination, a source of electric current, a plurality of motors adapted to be supplied from said source, a compressor driven by one of said motors, unloading means for said compressor, compressor discharge pressure governed controlling means for said unloading means, and means for taking the control of said unloading means away from said last mentioned means governed by the current drawn from said source by said plurality of motors including means for bypassing the compressor discharge pressure governed means, said current controlled means being operative only upon a predetermined amount of current flow. 110 115 120

5. In combination, a source of electric current, a plurality of motors adapted to be supplied from said source simultaneously while carrying a normal full load, a compressor driven by one of said motors, unloading means for said compressor, compres- 125 130

sor discharge pressure governed controlling means for said unloading means, and means for taking the control of said unloading means away from said last mentioned means governed by the current drawn from said source by said plurality of motors including solenoid controlled bypass means for shunting said compressor discharge pressure governed means.

6. In combination, a source of electric current, a plurality of motors supplied therefrom, a compressor driven by one of said motors, a solenoid through which all the current passing to said motors flows, and means controlled by said solenoid for unloading the compressor when current in excess of a predetermined amount flows through said solenoid.

7. In combination, a source of electric current, a plurality of motors supplied therefrom, a compressor driven by one of said motors, a solenoid through which all the current passing to said motors flows, and means controlled by said solenoid for unloading the compressor when current in excess of a predetermined amount flows through said solenoid, said last mentioned means including an electrically controlled valve mechanism and a controlling switch for the latter controlled by said solenoid.

8. In combination, a source of electric current, a plurality of motors supplied therefrom, a compressor driven by one of said motors, a fluid pressure operated unloading mechanism for said compressor, a pilot valve for supplying fluid pressure thereto and

venting fluid therefrom, a connection from a source of pressure leading to said pilot valve, a bypass around said pilot valve, and means in said bypass automatically controlled to effect unloading of said compressor only when the amount of current flow from said source to said plurality of motors reaches a predetermined amount.

9. In combination, a compressor having a fluid operated unloading mechanism, and means for rendering the same operative including a circuit in which current flows throughout running of the compressor and in which current below a predetermined value will flow without affecting said unloading mechanism, means independent of said compressor for varying the current flow in said circuit, and means whereby when said current flow reaches a predetermined amount fluid is admitted to said unloading mechanism to render the same operative.

10. In combination, a compressor, a plurality of motors including a motor for driving said compressor, a source of electric current for driving said motors, unloading means adapted to unload said compressor upon actuating medium being supplied to said means, compressor discharge pressure governed controlling means for the supply of such medium, and means governed by a predetermined amount of current drawn from said source by said plurality of motors controlling the supply of such medium.

In testimony whereof I affix my signature.

CHARLES B. OFFICER.
